ALBERT H. PERRY, OF HARTSHORN, ALBERTA, CANADA.

REGISTERING INSTRUMENT.

1,301,313.

Specification of Letters Patent. Patented Apr. 22, 1919.

Application filed July 9, 1917. Serial No. 179,591.

To all whom it may concern:

Be it known that I, ALBERT H. PERRY, a subject of the King of Great Britain, residing at Hartshorn, in the Province of Alberta and Dominion of Canada, have invented certain new and useful Improvements in Registering Instruments, of which the following is a specification.

This invention has relation to registering instruments and has for an object to provide a device adapted to be associated with a cream separator whereby the number of revolutions of the crank may be indicated per unit time.

Another object of the invention is to provide a registering instrument of the character above stated embodying means for indicating the passage of a period of time, and means operable at each revolution of the crank shaft of the cream separator to register the revolution and to total the number of revolutions during the passage of the aforesaid period of time.

A still further object of the invention is to provide a device of this character adapted to be automatically reset to initial position subsequent to the expiration of a definite period of time whereby the number of revolutions of the crank may be again indicated without arresting operation of the cream separator or adjustment of the device.

In addition to the foregoing my invention comprehends improvements in the details of construction and arrangement of the parts to be hereinafter more fully described and particularly set forth in the appended claims.

In the accompanying drawings in which similar and corresponding parts are designated by the same characters of reference throughout the several views in which they appear:

Figure 1, is a view in elevation of a registering instrument constructed in accordance with my invention illustrating the face view thereof.

Fig. 2, is a view on an enlarged scale of the device with the face plate thereof removed.

Fig. 3, is a section taken through the device along the line 3—3 of Fig. 2, and

Fig. 4, is a view in elevation of a cream separator illustrating the application thereof to my invention.

With reference to the drawings 10 indi-

cates the casing of the instrument, which may be circular, and is provided with a frame work 11 for supporting the mechanism which includes a central timing shaft 12 journaled at one end for rotation, in the frame 11 and at its opposite end in a sleeve 13 which extends without the casing and is provided with a finger engaging head 14 whereby the sleeve may be rotated. The 60 sleeve 13 carries thereupon interiorly of the casing a ratchet wheel 15 to one face of which one end of a coil spring 16 is connected as indicated at 17, the opposite, or inner end of said spring being connected to the 70 shaft 12. Said timing shaft 12 is also provided with a pinion 18 which meshes with a relatively small pinion mounted upon a shaft 19 journaled in bearings formed in an extension 20 of the frame 11. The shaft 19 75 also carries an escapement wheel 21 which operates in connection with an escapement lever 22 mounted for oscillation about a point 22', the opposite end of the lever being adapted to rotate in alternate directions 80 a balance wheel 23 pivotally supported by a frame arm 24. The balance wheel is provided with the usual hair spring, and it will be apparent that under the tension of the spring 16, the shaft 12 and pinion 18 are 85 rotated, the rate of rotation being controlled through the escaping mechanism the rate being preferably one revolution of the shaft 12 per minute. The shaft 12 is extended 90 through the face plate of the casing and is provided with a hand 25 which rotates over the face and indicates the divisions of time upon a circular scale 26. The spring 16 is wound through the medium of the finger engaging head 14 and the spring is held under 95 tension through the medium of a pawl 27 mounted upon the bottom of the casing and which engages the periphery of the ratchet wheel 15.

The wheel 18 is adapted for meshing engagement with a pinion 28 which is slightly smaller than the pinion 18, and is mounted for sliding movement upon a shaft 29 parallel with the shaft 12 and is journaled at one end in the frame 11 and at its opposite 105 end in a sleeve 30, similar to the sleeve 13 mentioned above and likewise journaled in the back plate of the casing. The pinion 28 is however keyed to the shaft 29 whereby it may rotate therewith. A spiral spring 31 encircles the shaft 29, with the inner end of the spring connected thereto, and the opposite

end connected, as indicated at 32, to one face of a ratchet wheel 33 which is fixedly secured to the sleeve 30. By rotating the sleeves 13 and 30 the springs 16 and 31 may 5 be placed slightly under strain before operation of the device, the springs being placed further under strain during operation. A pawl 34 pivoted upon the back plate of the casing serves to prevent rotation of the 10 ratchet wheel in one direction. The upper face of the pinion 28 carries a clutch element 35 which is complementary to a clutch element 36 mounted upon a resetting device 37 which comprises a plurality of radial 15 arms 38, said device being loosely mounted upon the shaft for rotation relative thereto. A coil spring 38' encircles the clutch element 35 and 36 and serves to retain the clutch element in separated relation by urging the 20 pinion 28 toward a lowermost position, sliding movement of the resetting device 37 being limited by the provision of a collar 37' on the shaft. The face of the pinion 28 opposite that carrying the clutch element 35 is 25 provided with a pin 39 which is located adjacent the periphery thereof for coaction with a cam element 40 mounted upon the corresponding side of the pinion 18 and adjacent the periphery thereof for engagement with 30 the pin 39 when said pin and cam elements are brought together during rotation of the pinions carrying the same.

A shaft 41 is journaled at its opposite ends in the frame 11 and back plate of the casing, 35 and has fixed thereto a ratchet wheel 42 which is located in the plane of the resetting device 37, said shaft 41 also carrying an arm 43 of resilient material which is fixed for rotation therewith. A pawl 44 mounted upon 40 a relatively stationary point is adapted to engage the periphery of the ratchet wheel 42 to prevent rotation thereof in one direction. An actuating pawl 45 is mounted for oscillation upon a fulcrum 46 and is provided with 45 a dog 47 pivotally connected to the outer end of the pawl, said dog being spring held and adapted for engagement with the periphery of the ratchet wheel 42. A coil spring 48, connected to the pawl 45 and at its opposite 50 end to a relatively stationary point, serves to normally retain the pawl 45 in an initial position, and to return the pawl to such position subsequent to oscillation thereof to an actuating position. An actuating rod 49 is 55 extended into the casing with its outer end projecting therefrom and provided with a button 50, and its inner end pivotally connected as indicated at 51, to the pawl 45. A rod 49' is mounted for axial movement adjacent the rod 49 and is disposed parallel thereto and provided at an intermediate portion with an elongated slot which receives a pin 46' mounted in the pawl 45. The inner end of the rod 49' carries a pawl 45' which 60 is adapted to engage the teeth of the central 65

wheel 18. The opposite end of the rod 49' is provided with a button 50' which extends beyond the edge of the casing and is located beneath the button 50 so as to be engaged by said button when the same is pressed inward in a manner which will be presently seen. The rod 45' is provided with a pair of spaced notches in which a spring 49'' is adapted to be engaged, one notch at a time according to the position of the rod. 70

A shaft 52 is disposed parallel to the shaft first mentioned, and disposed in close proximity to the shaft 29 and supports a ratchet wheel 53 which is fixedly secured thereto, said ratchet wheel being located preferably 80 in the plane of the first mentioned ratchet wheel 42. A spiral spring encircles the shaft 52 with its inner end connected to the shaft and its outer end connected as at 54 to a relatively stationary point. A pawl 55 is 85 pivotally mounted as at 56 to a relatively stationary point for engagement with the periphery of the ratchet 53, said pawl having an arm 56 which is disposed in the path of movement of the radial arms 38 of the resetting device. The upper face of the ratchet wheel 53 is also provided adjacent its periphery with ten uniformly and circumferentially spaced pins 57, said pins being adapted to be struck one at a time by 90 the arm 43 which as mentioned above, is carried by the shaft 41. It will be noted from Fig. 1 of the drawings, that the shafts 41 and 52 extend through the front face of the casing and are provided with hands 58 and 59 respectively which travel around a circle of graduations, divided into tenths. 95

The application of my registering instrument to a cream separator is set forth in Fig. 4 of the drawings, wherein it will be noted 105 that 60 indicates the standard and 70 the crank shaft which actuates the separating mechanism in a manner well known in this art. The crank shaft is provided with an operating crank which includes a radial arm 110 71 having a handle portion which comprises a bolt 72 secured to the extremity of the arm 71, said bolt being surrounded by a sleeve 73, rotatable relatively to the bolt. An arm 74 is secured at one end to the sleeve, and the 115 instrument is affixed to the opposite end of said arm 74. The arm 71 is furthermore provided with a lug 75 which is adapted to be engaged by the button 50 of the instrument. Thus it will be seen that if the portion 73 of the handle is firmly grasped and held, and the crank rotated, the button 50 of the instrument will be engaged by the lug 75 once during every revolution of the crank, and consequently of the crank shaft 70. 120 The first engagement of the button 50 will also move the rod 49 axially whereby the pawl 45' will be disengaged from the central wheel 18 to permit operation of the timing mechanism. At each engagement of the 130

button 50, the rod 49 will be moved longitudinally whereby to oscillate the pawl 45 which in turn rotates the ratchet wheel 47' partially, preferably one-tenth of a revolution for each engagement of the button 50. The hand 58 on the face of the instrument will thus be intermittently moved around the graduation circle adjacent thereto to indicate successive engagements of the button 50, the scale being graduated from zero to nine, a complete revolution of the hand 58 thereby indicating ten revolutions of the crank shaft. During rotation of the ratchet 42, the arm 43 is moved around the shaft 41, and the free extremity of the arm engages one of the pins 57 of the ratchet 53 at each complete revolution of the shaft 41. The result therefore will be to rotate the ratchet 53 one-tenth of a revolution after each complete revolution of the ratchet 42. The hand 59 on the face of the disk therefore serves to indicate tens and the hand 58 units. In view of this, where the hand 25 completes its circumscribed path about the face of the dial scale 26, the number of revolutions of the crank shaft will be indicated by observing the position of the hands 58 and 59 relative to the graduations adjacent thereto.

Just prior to the completion of a revolution of the central timing shaft 12 and consequently the hand 25 carried thereby, the cam member 40 engages the pin 39 of the pinion 28 which pin will be at that time located in a position to be engaged by the cam member, owing to the fact that the pinions 18 and 28 rotate in unison. The pinion 28 will be shifted upon its shaft so as to bring the clutch members 35 and 36 into engagement, and to disengage the pinion 28 from the pinion 18. It will be noted that the diameter of the pinion 28 is exactly one-half the diameter of the pinion 18 thereby insuring the engagement of the cam 40 with the pin 39 at each complete revolution of the shaft 12. The spring 31 of the shaft 29 being under tension, serves to rotate said shaft 29 in a direction reverse from its direction of rotation during rotation of the center pinion 18, thereby carrying the resetting device 37 around with the pinion 28. The arms 38 will thus be rapidly rotated and upon engaging the periphery of the disk 42 will rotate the same until the arm 43 movable with said disk 42, engages a stop pin 76 stationarily mounted relative to the casing. Rotation of the arms 38 of the resetting device will also serve to engage the arm 56 of the pawl 55 whereby to release said pawl from engagement with the disk 53, which disk will be rotated and the hand 59 carried by the shaft 52, returned to zero, the motion of the shaft being arrested through the provision of a radial arm 77 carried by the shaft which engages a pin 78 stationarily mounted relative to the casing. It is to be

noted in this connection that rotation of the disk 53 intermittently through engagement of the pins thereof by the arm 43, will serve to place the spring which encircles said shaft, under tension, the tension being released subsequent to disengagement of the pawl 55 as mentioned above. Thus, by the time the hand 25 reaches the zero point on the dial, the hands 58 and 59 will have been returned to zero, and a subsequent registering of the number of revolutions of the crank shaft may be begun immediately. Owing to the fact that the instrument is held upon the handle portion 73, which is grasped as stated above, the face of the instrument may be constantly observed and the rotation of the crank shaft produced uniformly thereby producing a uniform product of the cream separator. This device may be applied to any type of cream separator, and if desired may be secured to a stationary portion of the cream separator and the button 50 engaged by a lug on the crank handle instead of the arrangement disclosed.

The operation of the device may be briefly stated as follows: During rotation of the crank shaft of the cream separator the button 50 of the registering device will be struck at each revolution of the crank shaft and moved inwardly and radially. At the first engagement of the button 50 the button 50' will also be moved inward thereby disengaging the pawl 45' from the pinion 18, said pawl being held in disengaged position by means of the spring finger 49'. At each inward movement of the button 50 the ratchet wheel 42 will be partially rotated thereby carrying around the spring arm 43. Just prior to the completion of one revolution of the ratchet wheel 42, one of the pins 57 of the wheel 52 is engaged by the arm 43 thereby rotating the ratchet wheel 52 through one-tenth of a revolution. The pinion 18 having been released in the manner above stated, the detensioning of the spring 31 will carry said pinion 18 around in a clockwise direction, its rate of movement being limited by the escapement mechanism shown, so as to carry around the hand 25 causing said hand to make a complete revolution in one minute. Pinion 28 being in meshing engagement with the pinion 18 the spring 31 is placed under tension through rotation of the pinion 18. Just prior to a completion of one revolution of the pinion 18 the cam 40 carried thereby engages the pin 39 thereby shifting the pinion 28 along its shaft so as to engage the clutch members 35 and 36 and to disengage the pinion 28 from pinion 18. The pinion 28 and the resetting device 37 are thus free to rotate under the detensioning movement of the spring 31, and as a result the arms 38 engage the periphery of the ratchet wheel 42 to reset or return the said ratchet wheel to normal or starting position.

sition, return movement of said ratchet wheel being limited by engagement of the spring arm 43 with the stop pin 76. The arms 38 will also engage the pawl 55 to release the 5 wheel 53 which is returned to starting position by detensioning of the spiral spring associated therewith. It will be noted that rotation of the ratchet wheels 42 and 53 act to carry around the hands 58 and 59 to indicate the number of revolutions of the crank 10 shaft during the period of one complete rotation of the hand 25.

While I have illustrated and described my invention with some degree of particularity, 15 I realize that in practice various alterations thereover may be made, and I therefore desire to reserve the right and privilege of changing the form of the details of construction or otherwise altering the arrangement 20 of the correlated parts without departing from the spirit of the invention or the scope of the appended claims.

Having thus described my invention what 25 I claim as new and desire to secure by Letters Patent is:—

1. In a registering instrument, a counting mechanism, means for actuating the same, a time indicating mechanism including a pinion adapted to complete one revolution 30 during the passage of one second of time, resetting mechanism for returning the counting mechanism to zero including a pinion in meshing engagement with the first mentioned pinion, a resilient element associated 35 with the second mentioned pinion and adapt-

ed to be placed under strain by rotation of said pinion when said rotation is induced by rotation of the first mentioned pinion, a pin on the second mentioned pinion, and a cam on the first mentioned pinion for engaging 40 the pin of the second pinion, once during every revolution of the first mentioned pinion whereby to move the second mentioned pinion out of engagement with the first whereby to release the resilient element to 45 permit actuation of the resetting mechanism, the second mentioned pinion returning to former engagement with the first subsequent to disengagement of the cam and pin.

2. In a registering instrument, a counting mechanism including a unit wheel having a peripheral series of teeth, means for intermittently rotating said unit wheel, time indicating mechanism, resetting mechanism including a plurality of radial arms adapted 55 to engage during rotation thereof, the teeth of the counting wheel, but normally out of engagement thereof, resilient means for rotating said arms, and means operable subsequent to the expiration of predetermined 60 periods of time to release the resilient means to permit rotation of said arms whereby to return the unit wheel to zero.

In testimony whereof I affix my signature in presence of two witnesses.

ALBERT H. PERRY.
